UNITED STATES PATENT OFFICE.

DUER BUCKLEY, OF TYRRELL, OHIO.

AUTO AXLE SUPPORT.

Application filed June 13, 1921. Serial No. 477,076.

To all whom it may concern:

Be it known that DUER BUCKLEY, a citizen of the United States of America, residing at Tyrrell, in the county of Trumbull and State 5 of Ohio, has invented certain new and useful Improvements in Auto Axle Supports, of which the following is a specification.

This invention relates to a front axle brace and a clamp for automobiles.

10 The principal object is to provide a device which will keep and support the front axle member in an upright position. Automobiles such as the Ford are provided with front axles formed so as to take the shape 15 of an I-beam. In order to hold this front axle in an upright or vertical position, manufacturers have attached a radius rod with the two ends secured underneath the front axle I-beam, near the outer ends, in order to keep 20 the same from tilting. The outer ends of said radius rod are provided with a hole, and are secured by means of bolts passing through a hole in the front axle, and through the hole in the end of said radius rod. 25 There is a continuous pressure on said radius rod which causes the hole in the end of said radius rod to become elongated, thereby allowing the front axle to tilt. This throws the front wheel attachment assembly out of 30 a vertical position, thereby making it difficult to steer the machine. Another bad effect caused by said tilting is to cause an uneven tread engagement with the road, thereby causing unnecessary wear on the front 35 tire.

In order to correct this tilting of the front axle, I have provided a front axle brace and clamp made in two parts. The clamping portion securely clamping the lower flange 40 of the I-beam of the front axle, while the other portion is secured to the radius rod immediately back of the front axle, and has an upwardly extending shoulder bracing the inner upper edge of the flange of the I-beam, 45 as above described.

With these and other objects in view the invention consists of certain novel combinations, constructions and arrangements of parts which will be hereinafter more fully 50 described and claimed.

In the accompanying drawings:

Figure 1 is a side elevation of the device properly installed.

Figure 2 is a top plan view of the device properly installed. 55

Figure 3 is a detail view showing the front axle in cross section, and one end of the radius rod assembled to the front axle without the device attached.

By referring to Figure 1 it will be seen 60 that I have provided a body portion 1 having a concave portion 2 which fits securely over the end of a radius rod 3, and is secured to said radius rod by means of a U-bolt 4, which straddles the end of the radius rod 3 65 and projects through the body portion 1 at points 5 and 6. This body portion 1 is provided with an upturned brace member 7, which fits securely against the inner flange 8 of the upper head 9 of the front axle or 70 I-beam 10. It will also be seen that this body portion 1 is provided with a longitudinal recess 11 into which fits the inner flange 12 of the lower head 13 of the front axle or I-beam 10. In order to hold this 75 body portion 1 in proper position, I have provided a clamping member 14 which fits over the outer flange 15 of the lower head 13 of the front axle or I-beam 10. This clamping member 14 is held in position by 80 means of a bolt 16 which passes through a hole in the base portion 17 of the clamping member 14, and through the base member 18 of the body portion 1.

By referring to Figure 3 it will be seen 85 that a bolt 19 passes through the front axle or I-beam 10, and through a hole 20 formed at the end of the radius rod 3. This radius rod 3 is installed to keep the front axle or I-beam 10 in an upright position, but as the 90 wheel 21 travels back or forth there is a tendency to loosen the nut 22, thereby exerting an undue force upon the front and back walls of the hole 20, thereby in time causing the same to be elongated. By means of my 95 device this condition is eliminated and the front axle or I-beam 10 held securely in an upright position.

What I claim is:

In a device of the class described, a body 100 portion, a concave portion formed on the underside of the said body portion so as to fit over the top of a radius rod, a U-bolt straddling said radius rod and projected upwardly through the body portion, an upturned brace member formed on the top of 105

said body portion, a recess formed in the body portion so as to fit over the inner lower flange of the front axle or I-beam, a clamping member formed to fit over the outer lower flange of said front axle or I-beam, a bolt securing said clamping member to said front axle or I-beam, and to the body portion of

the device, substantially as described for the purpose set forth.

In testimony whereof I affix my signature. 10
DUER BUCKLEY.
